UNITED STATES PATENT OFFICE.

EMMETT W. STULL, OF JOHNSTOWN, PENNSYLVANIA, ASSIGNOR TO THE LORAIN STEEL COMPANY, OF PENNSYLVANIA.

CONTROLLER FOR ELECTRIC MOTORS.

SPECIFICATION forming part of Letters Patent No. 665,144, dated January 1, 1901.

Application filed June 16, 1900. Serial No. 20,545. (No model.)

To all whom it may concern:

Be it known that I, EMMETT W. STULL, of Johnstown, in the county of Cambria and State of Pennsylvania, have invented a new and useful Improvement in Controllers for Electric Motors, of which the following is a full, clear, and exact description, reference being had to the accompanying drawings, which form a part of this specification.

10 My invention has relation to certain new and useful improvements in controllers for electric motors, and more particularly to series-parallel two-motor controllers of that type which employ a main moving element or drum carrying the series-parallelizing contacts and also a cut-out switch by means of which either motor, if injured, may be removed from circuit and the remaining motor operated alone.

My invention is designed to provide means 20 of improved character whereby under the condition just stated—that is to say, when but one motor is in circuit—the main element or drum of the controller will be automatically prevented from being moved beyond its last

25 series position, thereby avoiding any confusion of circuits or undesirable circuit conditions which might otherwise occur. This object I accomplish by providing a stop or lock for the main moving element or drum, together with an electromagnet, which under normal conditions with both motors in circuit holds said stop in retracted inoperative position, but which when either motor is removed from circuit is thereby deenergized and 35 loses its control of said stop, which thereupon assumes a position to prevent movement of the main element or drum beyond a certain predetermined position.

My invention also consists in the novel construction, arrangement, and combination of parts hereinafter described, and pointed out in the appended claims, reference being had to the accompanying drawings, forming a part of this specification, and to letters of reference thereon.

In the said drawings, Figure 1 is a diagram showing a development in plane of a controller embodying my invention and the circuit connections between the same and a pair of elec-

tric motors, and Fig. 2 is a detail view showing the stop or locking device and magnet. 50

The controller shown in Fig. 1 is, in general, of that type manufactured by The Lorain Steel Company and known commercially as the "No. 38" controller. A is the main 55 drum, having the contacts *a* and coöperating contact-fingers *b*, and B is a combined reversing and cut-out switch of the rotary type, having contacts *c* and coöperating fingers *d*. This switch has an intermediate "off" position and 60 six operative positions, the effects of which are indicated on the drawings, respectively, as "Ahead," "No. 1 ahead," "No. 1 back," "Back," "No. 2 back," and "No. 2 ahead"—that is to say, it has one position in which the 65 car is driven ahead with both motors, another position in which the car is driven back with both motors, and other positions in which the car may be propelled in either direction by either motor alone. The two motors are des- 70 ignated as "No. 1" and "No. 2." R indicates artificial resistance for connection in circuit with the motors.

By reference to the diagram it will be readily seen that the conductor P, which connects 75 the sixth finger *d* of the reversing and cut-out switch with the fifth finger *b* of the series-parallelizing drum, carries no current, except at such times as the reversing and cut-out switch is on either its main ahead or its main 80 back position, since said switch has no contacts for engagement with the said finger *d* in any of its other positions. In this conductor P, I place an electromagnet M and provide said magnet with a pivoted armature N. 85 Attached to said armature is a spring S, whose normal action it is to hold the armature in such a position that its free end will be in the path of a stop projection *p* on the shaft A' of the drum A. This stop projection is defi- 90 nitely positioned with respect to the contacts on the drum, so as to engage the said armature and stop the drum at a certain predetermined point, which is, preferably, when the drum is at the position indicated by the vertical line 95 5. This can occur, however, only when the reversing and cut-out switch is at one of its one-motor positions, since when said switch

is at either its main ahead or main back positions the magnet M is energized and, overcoming the action of the spring S , retracts the armature N out of the path of the stop 5 projection p .

It will be observed that in the particular controller shown the invention requires no change whatever in the position, arrangement, or number of contacts, and to apply the 10 invention to any controller of the general type to which it relates it is necessary only to provide the magnet and stop and to connect the magnet in a conductor which carries current only when both motors are in circuit. If in 15 a particular controller no such conductor is present, additional contacts may be provided for this purpose, and the magnet can then be connected in circuit between them. Various forms of stops may also be employed, since 20 any device arranged to engage a moving part of the main drum and to be retracted from a position of engagement by the action of a magnet is clearly within the scope of my invention. I do not therefore limit myself to 25 the particular construction and arrangement which I have herein shown and described.

Having thus described my invention, what I claim, and desire to secure by Letters Patent, is—
30 1. In an electric-motor controller, the combination with a conductor which carries current only when all the motors governed by the controller are in use in circuit, of an electromagnet having its coil connected with said 35 conductor, and a stop device for a moving element of said controller arranged to be retracted by said magnet.

2. In an electric controller, having a main moving element provided with contacts and connections for connecting two motors either 40 in series or in parallel, and also a second switch by means of which either of said motors may be cut out of circuit, a stop device for limiting the movement of said main moving element, and a magnet for holding said 45 device inoperative when both motors are in circuit, and for releasing said device when either motor is removed from circuit.

3. In an electric controller, having a main moving element provided with contacts and 50 connections for connecting two motors either in series or in parallel, and also having a switch for cutting either one of said motors out of circuit, of a stop arranged to engage and limit the movement of said main moving 55 element, and an electromagnet for holding said stop in inoperative position, said magnet having its coil connected with a conductor which carries current only when both motors are in circuit.

4. In a controller for two electric motors, the combination with the main moving element, of a stop device for limiting the movement of said element, a magnet for holding said stop in an inoperative position, and circuit 6; connections whereby said magnet is active only when both motors are connected in circuit.

In testimony whereof I have affixed my signature in presence of two witnesses.

EMMETT W. STULL.
